CLAIM

The ornamental design for a model vehicle motor mount as shown and described.

DESCRIPTION

FIG. 1 is a rear elevation view of a model vehicle motor mount showing our new design;

FIG. 2 is a front elevation view thereof;

FIG. 3 is an upper plan view thereof;

FIG. 4 is a lower plan view thereof;

FIG. 5 is a right-side elevation view thereof;

FIG. 6 is a left-side elevation view thereof;

FIG. 7 is an upper, right, front perspective view;

FIG. 8 is a lower, right, front perspective view thereof;

FIG. 9 is an upper, left, rear perspective view thereof; and,

FIG. 10 is a lower, left, rear perspective view of the model vehicle motor mount.

In the drawings, the broken lines illustrate portions of the model vehicle motor mount that form no part of the claimed design.
